[57] CLAIM

The ornamental design for a tooth cleaning implement, or similar article, substantially as shown and described.

DESCRIPTION

FIG. 1 is a perspective view of a tooth cleaning implement, or similar article, showing my new design;
FIG. 2 is a bottom plan view thereof;
FIG. 3 is a rear elevational view thereof;
FIG. 4 is a top plan view thereof;
FIG. 5 is an end view thereof as viewed from the left side of FIG. 2, the other end being a mirror view thereof; and
FIG. 6 is a cross-sectional view thereof taken along line VI—VI of FIG. 2.
The stippling in FIGS. 1, 4 and 6 denote a rough surface.
